UNITED STATES PATENT OFFICE.

SEBASTIANO MARZOCCIO, OF NEW YORK, N. Y.

GAS-BURNING RANGE.

1,215,679.

Specification of Letters Patent. Patented Feb. 13, 1917.

Application filed March 3, 1916. Serial No. 81,826.

To all whom it may concern:

Be it known that I, SEBASTIANO MARZOCCIO, a citizen of the United States, residing at the city of New York, borough of Manhattan, in the county and State of New York, have invented certain new and useful Improvements in Gas-Burning Ranges, of which the following is a full, clear, and exact specification.

10 This invention relates to an improvement in stoves and ranges, and the like, adapted to be operated by a fluid fuel, and the same has for its object more particularly to provide a burner for the fuel which will direct 15 the flame against the portion or portions of the stove or range where a high degree of heat is desirable for cooking or heating purposes.

Further, the invention has for its object to 20 provide a burner having pipes for directing the flame against one portion of the stove or range which pipes are provided with branches for directing the flame against another portion of the stove or range.

25 A further object is to provide the fire-pot of ranges of this type with heat-retaining members which are so supported therein that there weight is not borne by the burner.

30 A further object is to so form the heat-retaining members that they will be quickly heated by the flame and will not tend to obstruct the flame from passing between them.

Other objects will in part be obvious and in part be pointed out hereinafter.

35 To the attainment of the aforesaid objects and ends, my invention consists in the novel details of construction, and in the combination, connection and arrangement of parts hereinafter more fully described and 40 then pointed out in the claims.

In the accompanying drawings, showing an illustrative embodiment of the invention—

Figure 1 is a front view of a range with 45 my improved burner applied thereto, parts being broken away;

Fig. 2 is a side view of the burner, parts being shown in section;

Fig. 3 is an end view of the burner, parts being shown in section, and 50

Fig. 4 is an elevational view on an enlarged scale of one of the heat-retaining elements.

While the improved burner may be used in connection with any suitable type of stove 55 or range it is shown, for purposes of illustration, as applied to a French range.

Referring to the drawings 10 indicates a range having a fire-pot 11 located between ovens 12, 12, as is usual in French ranges. 60 Positioned within the fire-pot 11, and supported in any suitable manner, as, for example, by brackets 13, is the burner.

The burner comprises a mixing chamber 15 provided with a plurality of outlets in 65 its upper surface communicating with a plurality of rows of pipes 16 and 17 secured to the mixing chamber 15 and extending upwardly therefrom. The pipes 17 which are arranged in a row centrally of the mixing 70 chamber 15 throughout the length thereof and between the rows of pipes 16 are of greater length than the pipes 16 and terminate a short distance below the top plate of the range. They are provided intermediate their 75 ends with oppositely-disposed, laterally-extending branches 18 and 19, the branches 18 being arranged above the branches 19 as clearly shown in Fig. 3. The branches 18 and 19 are of such a length that they terminate adjacent the inner walls of the ovens 12, 12, and are so inclined with respect to the pipes 17 that the branches 18 serve to direct the flame against the upper portions of the oven walls while the branches 19 serve to direct the flame against the lower portions 85 thereof.

The pipes 16 and 17 and also the branches 18 and 19 are preferably surrounded by a jacket 20 of refractory material in order to 90 protect them from being burned or otherwise damaged by the heat.

In order to conserve and store the heat the fire-box 11 is filled with a plurality of heat-retaining members 21 supported upon 95 a suitable grid 22 mounted within the fire-

box 11 in any suitable manner and spaced from the upper surface of the mixing chamber 15 so that the weight of the members 21 will not be borne by the burner.

- 5 The heat-retaining members 21 are made of fire-brick, fire-clay, lava, or any other suitable refractory material and are in the form of hollow spheres having diametrically-disposed apertures 23 in their walls 10 and provided upon their outer surfaces with a plurality of projections 24. The apertures 23 permit the flame to pass through the hollow members 21 whereby they will be quickly heated and the projections 24 serve 15 to space the members from one another sufficiently to permit the flame to pass freely between them thus avoiding any choking of the flame which might otherwise occur.

The gas and air, which forms the combustible mixture, are directed into the mixing chamber 15 through the lower wall thereof by pipes 25 and 26, respectively, of any suitable construction, the amount of air passing through the pipe 26 being controlled by 25 a suitable regulating valve as is usual in burners of this general type.

In operation when the burner is lighted the heat-retaining members 21 will absorb and store the heat from the flame, thus effecting a saving in the amount of gas used. As the central row of pipes 17 will direct the flame against the top plate of the range and as the branches 18 and 19 will direct the flame against the inner walls of the oven, 30 these parts of the range will be subjected to a high degree of heat thereby insuring that the cooking operations will be facilitated.

Having thus described my said invention, what I claim and desire to secure by Letters Patent is:—

1. A burner comprising a mixing chamber and a pipe having one end communicating therewith and its other end open, said pipe being provided with oppositely-disposed, laterally-extending branches communicating therewith intermediate the ends thereof, substantially as specified.

2. A burner comprising a mixing chamber and a pipe having one end communicating therewith and its other end open, said pipe being provided with laterally-extending branches communicating therewith intermediate the ends thereof, the point of communication of one of said branches being nearer the open end of said pipe than is the point of communication of the other of said branches, substantially as specified.

3. A burner comprising a mixing chamber and an open-ended pipe extending upwardly therefrom and communicating therewith, said pipe being provided with open-ended branches communicating therewith intermediate the ends thereof, the open end

of one of said branches being positioned in a plane below the plane of the open end of the other of said branches, substantially as specified.

4. A burner comprising a mixing chamber and an open-ended pipe extending upwardly therefrom and communicating therewith, said pipe being provided with oppositely-disposed, open-ended branches communicating therewith intermediate the ends thereof, the open end of one of said branches being positioned in a plane below the plane of the open end of the other of said branches, substantially as specified.

5. A burner comprising a mixing chamber, a plurality of rows of pipes communicating therewith, a row of pipes provided with laterally-extending branches and communicating with said mixing chamber, said row of pipes being positioned between two adjacent rows of said plurality of rows of pipes, substantially as specified.

6. A burner comprising a mixing chamber, a plurality of rows of pipes communicating therewith, a row of pipes provided with laterally-extending branches and communicating with said mixing chamber, said row of pipes being positioned centrally of said mixing chamber and between two adjacent rows of said plurality of rows of pipes, substantially as specified.

7. A burner comprising a mixing chamber, a plurality of rows of pipes communicating therewith, a row of pipes provided with laterally-extending branches and communicating with said mixing chamber, the pipes of said row being longer than the pipes of said plurality of rows, said row of pipes being positioned between two adjacent rows of said plurality of rows of pipes, substantially as specified.

8. A burner comprising a mixing chamber, a plurality of rows of pipes communicating therewith, a row of pipes provided with oppositely-disposed branches and communicating with said mixing chamber, said row of pipes being positioned between two adjacent rows of said plurality of rows of pipes, substantially as specified.

9. A burner comprising a mixing chamber, a plurality of rows of pipes communicating therewith, a row of pipes provided with oppositely-disposed, laterally-extending branches and communicating with said mixing chamber, said row of pipes being positioned between two adjacent rows of said plurality of rows of pipes, substantially as specified.

10. A burner comprising a mixing chamber, a plurality of rows of pipes communicating therewith, a row of pipes communicating with said mixing chamber and positioned between two adjacent rows of said

plurality of rows of pipes, each of the pipes of said row of pipes being provided with laterally-extending branches communicating therewith, the outlet of one of said branches being positioned at a greater distance below the outlet of its associated pipe than is the outlet of the other of said branches, substantially as specified.

Signed at the city of New York, in the county and State of New York, this 4th 10 day of February, one thousand nine hundred and sixteen.

SEBASTIANO MARTOCCIO.
